[57] CLAIM

The ornamental design for a combined mouse pad with a calculator, as shown and described.

DESCRIPTION

FIG. 1 is a perspective view of the combined mouse pad with a calculator showing my new design;
FIG. 2 is a top plan view thereof;
FIG. 3 is a bottom plan view thereof;
FIG. 4 is a side elevational view thereof, the opposite side is identical;
FIG. 5 is an end elevational view thereof, the opposite end is identical;
FIG. 6 is a partial cross-sectional view thereof, taken on line 6—6 of FIG. 2, on an enlarged scale; and,
FIG. 7 is a partial cross-sectional view thereof, taken on line 7—7 of FIG. 2, on an enlarged scale.
